No. 853,083.

PATENTED MAY 7, 1907.

C. HASTY.
SIGN DISPLAYING DEVICE.
APPLICATION FILED JULY 31, 1906.

UNITED STATES PATENT OFFICE.

CHARLES HASTY, OF LA FAYETTE, INDIANA.

SIGN-DISPLAYING DEVICE.

No. 853,083.

Specification of Letters Patent.

Patented May 7, 1907.

Application filed July 31, 1906. Serial No. 328,624.

To all whom it may concern:

Be it known that I, CHARLES HASTY, a citizen of the United States, residing at La Fayette, in the county of Tippecanoe and State 5 of Indiana, have invented certain new and useful Improvements in Sign-Displaying Devices, of which the following is a specification.

This invention relates to improvements in sign displaying devices.

10 The invention contemplates the provision of a simple, strong and sightly device of this character in which the letters on the sign or the intelligence to be conveyed thereby, will be clearly and distinctly visible in the day, 15 and which may be illuminated at night in such a way that the letters or devices thereon will be clearly visible at that time.

15 The invention comprises in the main a device in circular form composed of two similar saucer-like, or concavo-convex frames disposed opposite to each other, so as to display the intelligence thereon to observers from both sides, and an intermediate disk or plate of opaque material to form a background for 25 the letters so that they may be more readily seen by day or night without confusing the intelligence displayed upon one side of the sign with that displayed upon the other.

20 The invention further contemplates such arrangement of the opaque disk with relation to the frames, that the wind will pass through the frames and letters and be deflected from the disk, thereby reducing to a minimum the chance of destruction of the device in wind 25 storms.

30 The invention further consists in details of construction relating to the manner of providing illumination by artificial light, as well as points of construction whereby the whole device is made durable and sightly. The sign 35 is illuminated on each side from a point slightly above the center, thus substantially dividing the rays of light with equality upon the letters upon the frame, and at the same 40 time avoiding obstruction to vision, so that the letters on the sign will be clearly visible and prominent.

45 The invention contemplates the general improvement of signs of this character by the provision of devices whereby the two sections and opaque disk are firmly held together, as well as the improvement of other details of construction which will become apparent in the course of the following description:

50 In the drawings: Figure 1, is a perspective view of a sign displaying device con-

structed in accordance with my invention, the means for supporting the device being omitted. Fig. 2, is a central section of the device taken at a point just in advance of the 60 cross-piece or arm by which the device is supported, and through which the sign may be illuminated. Fig. 3, is a top plan view of a plate used in connection with the central main clamping plate. Fig. 4, is a similar 65 view of one section of the clamping plate into which the radiating wires of the sections or frames run, and are fastened.

Referring to the drawings, the numeral 1, designates two saucer-like concavo-convex 70 frames formed of wire bent in circular form. The frames are identical in construction, and it will be understood that reference to one will likewise apply to the other.

The numeral 2, designates the outer wire 75 which incloses a similar circular wire 3. The wire 3 is crossed by a series of radiating wires 4, secured to the wire 3 at points of crossing by wire ties 5, and the ends of the wires 4 are extended to points 6 where eyes are formed 80 embracing the outer wire 2. The inner portions of the wires 4 pass through a series of radiating grooves or recesses 7, beyond which their ends are bent sharply downward as indicated at 8, and embedded in a bed of soft 85 metal 9, which is contained in the depression 10 of two clamping plates 11. These clamping plates are each provided with two central openings 12, for the passage of a clamping 90 screw 13, which passes through two circular plates 14 also provided with central openings 15. The plate 14 is provided with a series of radiating grooves or depressions which fit over the ends of the wires 4, and lock them 95 firmly in place.

Clamped between the clamping plates 11, is an opaque disk 16 preferably painted black, forming a background against which the letters upon the sign stand out boldly.

To insure the rigidity of the sign I provide 100 a number of cross-pieces 17 secured to the outer wire of each section of the sign. These cross-pieces are preferably connected to the wires by eyes, and pass through apertures 18 in the disk 16.

At the top of the sections, and rigidly secured thereto, at points 19, is a transverse arm 20 extended downwardly in approximately semi-circular form, where at its ends are fitted two sockets 21 for incandescent 110 electric light bulbs, or the ends may be so fitted as to adapt them to support ordinary

lamps or other illuminating devices in common use, as the exigencies of the situation may make more convenient. The ends of the bowed portions of the arm 20 terminate at points just above the center of the two sections, so that the lighting devices, while radiating their rays with substantial uniformity upon all of the intelligence upon the sign, will not obstruct the free vision of any of the matter displayed upon the sign.

Where electric lights are employed, the arm 20 is preferably tubular, thereby forming a conduit for the electric wires and thus protecting them from injury and insulating them against danger.

Extending transversely of each section are preferably three wires 22 which form a support for the rectilinearly disposed letters 23, of the sign. The letters may be made of any suitable material and formed with tongues which are folded over the wires at the ends of the letters. The letters which are displayed in circular form upon the frames embrace the outer wires 2, and the inner wires 3, and while they are held to the wires in the way just suggested, it is obvious that they may be secured to their supports by any convenient means, such as wire ties or the like.

I have omitted the means for supporting the sign, but it will be understood that it may be supported by any convenient means and suitably guyed as the situation surrounding its use, may demand.

Claims.

1. A sign displaying device comprising two oppositely disposed concavo-convex skeleton frames rigidly attached together at their centers, an arm attached to the outer edge of each frame and serving as a brace and light holder and having a portion extending downwardly to a point at or near the center of each frame, the lower ends of said downwardly extending parts being provided with means for artificially illuminating the intelligence upon the frames, substantially as described.

2. A sign displaying device comprising two oppositely disposed skeleton frames rigidly clamped together at their centers, a disk or plate of opaque material arranged between the frames and clamped to said frames at its central point, and a centrally located means for firmly clamping the two frames and the disk together.

3. A sign displaying device comprising two oppositely disposed concavo-convex wire frames, two oppositely disposed central clamping plates formed for the reception of the radiating wires of the frame sections, and an auxiliary clamping plate for each of the main clamping plates, a bolt for securing all of the clamping plates together, a disk or plate interposed between the wire frames and held in position by the clamping plates, substantially as described.

4. A sign displaying device comprising two oppositely disposed concavo-convex frames formed of outer wires presenting rims 2, inner concentric wires 3, radially arranged wires 4, a centrally positioned clamp embracing the inner ends of the radiating wires, a disk or plate of opaque material interposed between the two frames for the purpose set forth, a series of strengthening wires attached to the edges of the outer circular wires, a cross-bar connected to the periphery of the frames and having extensions fitted for the reception of illuminating devices, substantially as and for the purpose set forth.

5. A sign displaying device comprising two oppositely disposed concavo-convex frames formed of wires presenting rims 2, and inner circular wires 3, radiating cross wires suitably secured to the wires 2 and 3, a centrally positioned clamp embracing the inner ends of the radiating wires at a central point for the purpose of holding the two frames together, a disk or plate of opaque material interposed between the two frames for the purpose set forth, and held by the central clamps, a transverse bed formed of wires, for the reception of letters in transverse arrangement upon the frames and means for illuminating the signs, substantially as and for the purpose set forth.

6. A sign displaying device comprising two oppositely disposed skeleton frames rigidly clamped together at a central point, a disk of opaque material clamped at the central point of the frames, means for firmly clamping the two frames and disk together, an arm attached to the edge of each frame and serving as a brace and light holder, and having a portion extending downwardly to a point at or near the center of each frame, the lower ends of said downwardly extending parts being provided with means for artificially illuminating the intelligence upon the frames, and a plurality of cross pieces or ties connecting the peripheries of each frame and passing through the disk or plate whereby the frames are braced together and the disk held in central position between the frames, substantially as described.

7. A sign displaying device comprising two oppositely disposed concavo-convex skeleton frames rigidly held together, an arm attached to the outer edge of each frame and serving as a brace and a light holder, and having a portion extending downward to a point at or near the center of each frame, the lower ends of said downwardly extending parts being provided with means for artificially illuminating the intelligence upon the frames.

In testimony whereof I affix my signature in presence of two witnesses.

CHARLES HASTY.
